DESIGN FOR AN END PIECE FOR ROPES OR THE LIKE

Siegfried Behr, Flushing, N. Y.

Application March 22, 1940, Serial No. 91,146

Term of patent 3½ years

To all whom it may concern:

Be it known that I, Siegfried Behr, a citizen of the United States, residing at Flushing, county of Queens, State of New York, have invented a new, original, and ornamental Design for an End Piece for Ropes or the like, of which the following is a specification, reference being had to the accompanying drawing, forming part thereof.

Fig. 1 is a front view of an end piece for ropes or the like showing my new design.

Fig. 2 is a bottom plan view thereof.

I claim:

The ornamental design for an end piece for ropes or the like, as shown.

SIEGFRIED BEHR.
